(57) **CLAIM**

The ornamental design for a racket, as shown and described.

DESCRIPTION

FIG. 1 is a perspective view of the present invention;
FIG. 2 is a right side elevational view of the present invention;
FIG. 3 is a top plan view of the present invention;
FIG. 4 is a front elevational view of the present invention;
FIG. 5 is a bottom plan view of the present invention;
FIG. 6 is a left side elevational view of the present invention;
FIG. 7 is a rear elevational view of the present invention;
FIG. 8 is a cross-sectional view taken on line 8—8 of FIG.
7; and,
FIG. 9 is a cross-sectional view taken on line 9—9 of FIG.
7.
